US00D922374S

(12) **United States Design Patent** (10) **Patent No.:** **US D922,374 S**
(45) **Date of Patent:** **** Jun. 15, 2021**

(54) **PORTABLE ELECTRONIC DEVICE**

(71) Applicant: **GETAC TECHNOLOGY CORPORATION**, Hsinchu County (TW)

(72) Inventor: **Wei-Sen Lu**, Taipei (TW)

(73) Assignee: **GETAC TECHNOLOGY CORPORATION**, Hsinchu County (TW)

(**) Term: **15 Years**

(21) Appl. No.: **29/765,927**

(22) Filed: **Jan. 12, 2021**

Related U.S. Application Data

(62) Division of application No. 29/656,336, filed on Jul. 11, 2018.

CLAIM

The ornamental design is for a portable electronic device, as shown and described.

DESCRIPTION

FIG. 1 is a top, front and right side perspective view of a portable electronic device showing my new design;

FIG. 2 is a top, rear and left side perspective view thereof;

FIG. 3 is a bottom, rear and left side perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof; and,

FIG. 9 is a bottom view thereof.
